E. & C. HICKS.
BELT HOLDER FOR ENGINES.
APPLICATION FILED JAN. 17, 1908.

900,538.

Patented Oct. 6, 1908.

UNITED STATES PATENT OFFICE.

ELMER HICKS AND CLARENCE HICKS, OF MONTEZUMA, IOWA.

BELT-HOLDER FOR ENGINES.

No. 900,538.

Specification of Letters Patent.

Patented Oct. 6, 1908.

Application filed January 17, 1908. Serial No. 411,835.

To all whom it may concern:

Be it known that we, ELMER HICKS and CLARENCE HICKS, both citizens of the United States, residing at Montezuma, in the county 5 of Poweshiek and State of Iowa, have invented a new and useful Belt-Holder for Engines, of which the following is a specification.

The object of this invention is to provide 10 means for retaining a belt on a pulley.

A further object of this invention is to provide a combined belt holder and fender, whereby a belt is retained on a pulley and the pulley is guarded against dangerous 15 manual contact while in operation.

A further object of this invention is to provide means whereby one operator can place a belt on the pulley of a traction engine, adjust a holder to said pulley and 20 back the engine in such manner as to tighten the belt without risk of accidental removal of the belt from the pulley.

Our invention consists in the construction, arrangement and combination of elements 25 hereinafter set forth, pointed out in our claims and illustrated by the accompanying drawing, in which—

Figure 1 is a rear elevation showing our device mounted as required for practical 30 use. Fig. 2 is a side elevation of the same. Fig. 3 is a side elevation illustrating the position occupied by the holder during the operation of placing or removing a belt from the pulley. Fig. 4 is a sectional view 35 on the indicated line 4—4 of Fig. 1. Figs. 5 and 6 are detail views of a modified construction.

In the construction of the device as shown the numeral 10 designates a bracket adapted 40 to be secured to some convenient part of a traction engine 11 contiguous to and on the inner side of a drive pulley 12 carried by and forming a part of said engine. An arm 13 is formed on and projects outwardly from 45 the upper end portion of the bracket 10 across the plane of and above the pulley 12, and said arm preferably is formed as a pivot or journal bearing. A hinge member 14 is journaled on and projects rearward from the arm 13 and a metal strap 15 is 50 fixed at one end to said hinge member. The strap 15 is of a length greater than one half the circumference of the pulley 12 and is curved concentric to the rim of said pulley 55 and is formed with a roll or eye at its end opposite to the hinge member. A slot 17

is formed in and longitudinally of the strap 15 between the center and the lower end of said strap. An arm 18 is fixed at one end to a suitable support, such as a stub axle 19 forming a part of the engine. The arm 18 extends outward from its support parallel with the axis of the pulley 12 and its outer end portion is bent rearward to form a hook 20 and is provided with a notch in its lower 65 face. The hook 20 extends through the slot 17 in the strap 15 and engages by its notch with the lower margin of said slot and retains the strap in a position concentric with and at the rear of the rim of the pulley 12. 70 A cross bar 21 is fixed at its center to and projects in opposite directions from the strap 15 adjacent the hinge 14 and guide rollers or pulleys 22, 23 are journaled on pins or bolts 24, 25 in and at right angles to the 75 ends of said cross bar. The guide rollers 22, 23 project radially of the pulley 12 and on opposite sides of the rim of said pulley. A cross bar 26 is fixed at its center to and projects in opposite directions from the strap 80 15 adjacent the roll or eye 16 and guide rollers or pulleys 27, 28 are journaled on pins or bolts 29, 30 in and at right angles to the 85 ends of said cross bar. The guide rollers 27, 28 project radially of the pulley 12 and on opposite sides of the rim of said pulley and are located materially lower than the rollers 22, 23.

When the strap 15 is detached from the hook 20 it can be separated from the pulley 90 12 a material distance as shown in Fig. 3, and when so separated a belt can be applied to or removed from the pulley by movement laterally. When the strap is positioned as shown in Figs. 1, 2 and 4 the pulleys 22, 27 on 95 one side and the pulleys 23, 28 on the other side form guides for the belt and may be engaged by the side margins of the belt and prevent accidental removal thereof from the pulley 12. By this means an operator can 100 mount a belt on the pulley of a grain separator and on the pulley 12 while the belt is slack, and then back up the traction engine and tighten the belt on the pulleys without risk of accidental removal of said belt from 105 the pulley 12. It will be observed, also, that the combined strap 15, cross bars 21 and 26 and the guide rollers form a fender for the drive pulley 12 and prevent accidental contact of the operator with said pulley. 110

It is desirable to provide adjustable means for connecting the strap to the support aux-

iliary to the hinge 14, and provision is made therefor in the construction shown in Figs. 5 and 6. In this construction the strap 15^a is imperforate and a plate 31 is formed with 5 loops 32, 33 snugly embracing the strap, the plate extending longitudinally of the strap and slightly curved. A slot 34 is formed in the central portion of the plate 31. A plate 35 is mounted on the outer end portion of 10 an arm 18^a and is adjustably secured thereto by a set screw 36. The plate 35 is curved to conform to the plate 31 and is provided with a lug 37 on its convex face, which lug is adapted in size and shape to enter and engage 15 in the slot 34. The plate 35 is formed with flanges 38, 39 on its side margins adapted to engage the side margins of the strap 15^a and prevent twisting of said strap. The plate 31 is connected adjustably to the strap 20 15^a by set screws 40, 41 in the loops 32, 33 engaging said strap, and said plate may be moved into any desired position in the length of said strap. Thus provision is made for adjusting the connection of the strap to 25 variously located supports, such as stub axle 19, and for adjusting the curvature of the strap concentric with variously sized pulleys, such as 12.

We claim as our invention—
30 1. A belt holder for engines, comprising a

strap pivotally mounted at one end and adapted to be moved through an arc, guide pulleys carried by said strap, and means for adjustably holding said strap concentric with a pulley rim.

35

2. A belt holder for engines, comprising a bracket, a strap hinged at one end to said bracket, cross bars on said strap, guide rollers on said cross bars, and detachable means for holding said strap concentric with the rim of a pulley.

3. A belt holder for engines, comprising a bracket, a strap hinged at one end to said bracket, cross bars on said strap, guide rollers on said cross bars, and detachable means 45 for holding said strap concentric with the rim of a pulley, said guide rollers projecting radially of said pulley and on opposite sides of the rim thereof.

4. A belt holder for engines, comprising a 50 bracket, a strap hinged at one end to said bracket, cross bars on said strap, guide rollers on said cross bars, an arm, and detachable connections between said arm and strap.

ELMER HICKS.
CLARENCE HICKS.
